DESIGN FOR A HOLDER FOR LENSES

Samuel Galper, Jamaica, N. Y.

Application March 8, 1944, Serial No. 112,817

Term of patent 7 years

(Cl. D80—5)

To all whom it may concern:

Be it known that I, Samuel Galper, a citizen of the United States, residing at Jamaica, in the county of Queens and State of New York, have invented a new, original, and ornamental Design for a Holder for Lenses, of which the following is a specification, reference being had to the accompanying drawing, forming part thereof.

In the drawing

Fig. 1 is a top plan view of a holder for lenses showing my new design;

Fig. 2 is a bottom plan view thereof;

Fig. 3 is a side elevational view; and

Fig. 4 is a front elevational view.

I claim:

The ornamental design for a holder for lenses, substantially as shown.

SAMUEL GALPER.
